UNITED STATES PATENT OFFICE

VASILY KOSMIN, OF NEW YORK, N. Y.

SHOE-SHINING MACHINE.

1,211,717.

Specification of Letters Patent. Patented Jan. 9, 1917.

Application filed January 8, 1916. Serial No. 70,940.

To all whom it may concern:

Be it known that I, VASILY KOSMIN, a subject of the Czar of Russia, and residing in the city of New York, county and State of New York, have made a certain new and useful Invention in Shoe-Shining Machines, of which the following is a specification.

This invention relates to shoe shining machines.

10 The object of the invention is to provide a coin controlled shoe shining machine which is automatically operated by the weight of the person using the same.

15 A further object of the invention is to provide a machine of the type described, which is simple in structure, economical of manufacture and efficient in operation.

Further objects of the invention will appear more fully hereinafter.

20 The invention consists substantially in the construction, combination, location and relative arrangement of parts, all as will be more fully hereinafter set forth, as shown in the accompanying drawing, and finally 25 pointed out in the appended claims.

Referring to the drawings, Figure 1 is a a top plan view of a machine partly broken to show a portion of the interior thereof, and embodying the principles of my invention. Fig. 2 is a view in side elevation of a portion of the same, enlarged and partly in central vertical section. Fig. 3 is a front view of the same, partly broken. Fig. 4 is a central longitudinal sectional view of the 35 center portion of the machine embodying my invention. Fig. 5 is a partly sectional view of the coin control mechanism employed in connection with my invention.

The same part is designated by the same 40 reference numeral wherever it occurs throughout the several views.

In accordance with my invention I provide a main body 1 provided with hollow cylindrical vertical standards 2 at the 45 proximate four corners of the machine. The body 1 is approximately square, as shown, and is provided with a hollow vertical shaft 3, at its approximate center. Slidably mounted in the shaft 3, is a shaft 4, adapted to be pressed downwardly against the action of spring 5, and having a foot 50 pedal 6 secured to it at its upper free end by any suitable means, such, for instance, as by the bolt 7.

55 Secured to the shaft 3, to rotate therewith, is a circular spider frame 8 provided with

three equi-distant radial arms 9. Each of the arms 9 is provided with a radial slot 10 as shown for a purpose to be hereinafter described. Surrounding the pedal 6, is an oval shaped slot 12, as shown in Fig. 1.

Extending through the slot 10 of each of the arms 9 of the spider 8, and through the oval slot 12, extend shafts 13, the upper end of each of which forms a universal joint 65 connection 14, with a shaft 15, which carries a brush 16. Thus it will be seen that by rotating the spider 8, the arms thereof will cause the shaft 13 to travel about the pedal 6 in the oval slot 12. To facilitate the movement of the shaft 13 in the oval slot 12, and the slot 10 of the spider arm, I provide the shaft with rollers 15 as shown in Fig. 2.

The brushes 16 may be of any desired shape, but I find it preferable to shape the 75 brush so that it conforms to the shape of the shoe 20 placed on the pedal 6.

As has been stated, I employ three brushes, one for each slotted arm of the spider and in accordance therewith one of 80 the brushes may apply the blackening or polishing paste, the next brush will shine the shoe, and the third brush being preferably constructed of soft material, such as 85 felt, or flannel, will polish the shoe.

In Fig. 2 I show the paste applying brush which is provided with a casing on one side indicated at 21. In this casing is the paste 90 22, which is normally pressed against the hairs of the brush 16 by the spring 23 which is suitably secured to the casing 21, as shown. Thus it will be seen that upon the rotation of the brush, the hairs sweep past and bear against the blackening material, and then apply it to the shoe to be polished. 95

It will be understood that to avoid confusion, I refer to blackening paste, but my invention is not to be limited to any color as it is obvious that the material 22 may be 100 of any desired color.

It is desirable to be able to have the brushes press against the shoe while it is being polished. For this purpose I secure to the slideable pin or shaft 4, a disk 25, which being secured to the shaft 4, is stationary 105 with respect thereto, but adjustable thereon by means of the nuts 81 to adapt the brushes to fit any size shoe. The end of this oval disk 25 projects between the two legs of a U-shaped member 26 attached to the frame 110 of the brush 16. The brush shaft having a universal joint connection 14, as has been

stated hereinbefore, it will be seen that pressure on the pedal 6 is transmitted to the brush 16 by the disk 25 thereby pressing the same against the shoe 20. Likewise when 5 the pressure is removed from the pedal 6, the spring 5 causes the pin or shaft 4 to rise thereby causing the disk 25 to force the upper leg of the U-shaped member 26 upward and rocking the brush 16 about its joint 14 10 out of contact with the shoe.

To facilitate the movement of the brushes around the slot 12 when under the pressure of the foot upon the pedal 6 as transmitted by the disk 25, I provide a roller 80 on the 15 lower leg of the U-shaped member 26, which roller bears against the under surface of the disk 25 as shown in Fig. 2.

In an upwardly extending frame 28, of the body of the machine is journaled a 20 sprocket 29 over which operates an endless chain 30. Secured to a shaft 32 suitably journaled in brackets 33, in the body of the machine is a sprocket 31 similar to the sprocket 29 and over which the endless 25 chain 30 also operates. Attached to the chain 30 by means of a suitable clamp 35, which clamps into or otherwise permanently engages a link of the chain, is a pedal 36, which is supported by tubes 37 suitably 30 mounted in the standards 2 of each side of the machine, which tubes are normally held to the top of the standards by springs 38 as shown in Fig. 5.

At the inner end of the shaft 32 is a bevel 35 gear wheel 40 which meshes with a similar gear wheel 41 mounted on the shaft 3 to drive the same.

It is desirable to secure rapid rotation of the brushes relative to the movement of 40 the spider 8. For accomplishing this I provide shaft 45 at each end of the oval on one of which is mounted a gear wheel 46, which meshes with and is driven by gear wheel 47 on the shaft 3. Also mounted on shafts 45, 45 are sprocket wheels 48 over which operate an endless chain 49. This endless chain is of double width, one upper portion of it operating over the sprocket wheel 48, and the other lower portion of it, as shown, in 50 Fig. 2, is in constant contact with a sprocket wheel 50 mounted on the shaft 13 of each brush. Thus it will be seen that when central shaft 3 is rotated, the spider arm rotates thereby causing the brushes to move 55 in the oval slot around the shoe, and also causing the brushes to rotate rapidly themselves. I show a simple arrangement for gearing up the chain 49 wherein I mount a sprocket on the shafts 45 and operate 60 thereover a chain 92. The pinion 46 and the sprocket rotate together and the sprockets of the chain 49 also rotate together but separate from the sprocket and chain 92 and pinion 46, as will be clearly understood. 65 While I have shown the pedal 36 at but one

side of the machine in Fig. 1, it will be understood that a similar pedal is located on the opposite side of the machine.

It is desirable to have the machine normally locked, but adapted to be unlocked by the insertion of a coin into the machine. Any suitable means for accomplishing this result may be employed. In Fig. 5, I show a simple arrangement wherein a coin 60 inserted in a slot 61 drops to bear against a cam wheel 62 in a groove 63, of a slidable rod 64, which is provided with an extension 65 which extends through the standard 2 and the tube 37, as shown. The cam wheel 62 when turned by the handle 66 forces the 70 coin 60 against the edge of the groove 63, thereby drawing the rod out of the standard and tube openings against the action of the spring 70, which causes the rod 64 to lock the machine again after the pressure 75 on the treadle or pedal 36 has been removed, thereby allowing the tube 37 to assume its normal position with respect to the standard 2.

The operation of the machine is exceedingly simple. The operator places one foot, say the right foot, on the foot rest or pedal 6, and exerts pressure thereon to secure the proper pressure of the brushes against the shoe, as hereinbefore explained. The machine is then released by the coin, and the operator places his other foot, in this case the left foot, upon the treadle or pedal 36, slowly depressing the same until it rests on the stop 90, see Fig. 2. The depression of 100 the pedal, due to its being connected to the chain 30, rotates the gear wheel 31, shaft 32, gear wheel 40, gear wheel 41, shaft 3, and spider frame 8, thereby causing one revolution of the shaft 3, and the spider frame 8, 105 which forces the three brushes once around the oval slot 12. When shaft 3 rotates, gears 47, 46, shaft 45, and gear wheels 48, are rotated thereby causing the double width chain 49 to rotate which in turn 110 causes the gear wheels 50 of each brush to rotate and thereby securing the individual rotation of each brush, as has been hereinbefore explained.

When the operation has been completed 115 the right shoe has been shined and polished completely around the exterior surface of the same, as will be readily understood. The foot is then withdrawn, the left foot placed on pedal 6, and the right foot on the 120 treadle 36 on the right hand side of the device, the machine released by the insertion of another coin and the operation hereinbefore described is repeated. It will be understood that the machine may also be operated by a motor geared in any conventional way to the shaft 3.

While I have shown and described one specific modification of my invention, it will be understood that many changes in de- 125 130

tail will readily occur to those skilled in the art without departing from the broad scope of my invention. Therefore

What I claim as new and useful, and of 5 my own invention, and desire to secure by Letters Patent of the United States, is,—

1. In a shoe polishing machine, the combination with a foot rest, brushes, means operated by the pressure of the foot upon 10 said foot rest to cause said brushes to bear toward the same, and means for individually rotating said brushes and to coincidentally rotate said brushes around said foot rest.

15 2. In a shoe polishing machine, the combination with a foot rest, brushes, means operated by the pressure of the foot upon said foot rest to cause said brushes to bear toward the same, a treadle for the other foot 20 of the operator, and means operated by the pressure of the foot upon said treadle for individually rotating said brushes and to coincidentally rotate said brushes around said foot.

25 3. In a machine of the class described, the combination with a foot rest for one foot of the operator, a plurality of individually rotatable brushes adapted to rotate thereabout, and a treadle operated by 30 the other foot of the operator for causing the rotation of said brushes, and means for locking said treadle in an inoperative position.

4. In a machine of the class described, the 35 combination with a foot rest for one foot of the operator, a plurality of individually rotatable brushes adapted to rotate thereabout, and a treadle operated by the other foot of the operator for causing the rotation of said brushes, and means for locking 40 said treadle in an inoperative position, and coin controlled means for releasing said locking means.

5. In a machine of the class described, the combination with a foot rest, a plurality of 45 brushes, adapted to rotate thereabout, and means operated by pressure on said foot rest to incline said brushes toward the same.

6. In a shoe polishing machine, the combination with a foot rest, brushes, a treadle 50 independent of said foot rest and mechanism driven by the depression of the foot upon said treadle for individually rotating said brushes, and rotating the same about 55 said foot rest.

7. In a machine of the class described, the combination with a vertical shaft, of a spider mounted on said shaft and provided with radial slotted arms, an oval slotted disk mounted on said shaft and stationary with respect thereto, a brush inserted through the slot of said disk and through one of the slotted arms of said spider, a treadle, and means operated by the depression of said treadle for rotating said 60 shaft, means for locking said treadle in an inoperative position and coin controlled means for releasing said locking means.

8. In a shoe polishing machine, the combination with a foot rest, brushes, means 70 operated by pressure upon said foot rest to cause the brushes to bear toward the foot rest, a treadle, and means operated by the depression of said treadle for individually rotating said brushes and for coincidentally 75 rotating said brushes around said foot rest.

9. In a machine of the class described the combination with a foot rest, a plurality of brushes adapted to rotate thereabout, and adjustable means operated by the pressure 80 on said foot rest to incline said brushes toward the same.

In testimony whereof I have hereunto set my hand on this 4th day of January, A. D., 1916.

VASILY KOSMIN.
